CONVEYING APPARATUS FOR CONTINUOUS STRIP MATERIAL

Carl E. Moore, Gary, Ind., assignor to American Sheet and Tin Plate Company, a corporation of New Jersey

Application August 24, 1934, Serial No. 741,305

2 Claims. (Cl. 271—2.3)

This invention relates to a conveying apparatus for continuous strip material, and more particularly to the product of modern sheet and tin plate mills wherein the work-piece is extremely long and of very thin gage, although not limited thereto.

This extremely long and thin gage material presents a troublesome problem from the standpoint of handling. The most convenient form of transferring such material is when it is coiled. However, when the strip is unwound for further processing, such as for continuous heat-treating, pickling, cleaning, side-trimming, sheared-to-length, or further recoiling, it must be handled in a manner which precludes the possibility of its wrinkling and/or kinking. In the majority of cases, these long lengths of strip have a high polish and smooth surface accruing from cold reducing operations which must be protected against scratching or rubbing.

It is often necessary to feed strip material of the type described from a continuously operating processing mechanism to one which operates intermittently and in so doing by-pass or avoid other equipment, such as furnaces, pickling tanks, coils, etc.

It is among the objects of the present invention to provide a novel conveying apparatus for continuous strip material which will effect a uniform feed or "flow", and particularly if such material is extremely long and unusually thin gaged.

Another object is the provision of devices of the class described which will feed extremely long lengths of continuous strip material over fixed equipment in the mill without its being scratched, kinked or otherwise damaged.

A further object is the provision of a conveying apparatus for continuous strip material which will function in the manner described and one which may, at the same time, be readily transported to various locations in the mill.

A still further object is to enable uniform feeding of extremely long and thin gaged strip material from a continuously operating machine to one which operates intermittently.

These and further objects will be apparent after referring to the drawings, in which:

Figure 1 is a sectional elevation of the device of the invention.

Figure 2 is an enlarged fragmentary elevation.

Figure 3 is a sectional view on the line III—III of Figure 1.

Figure 4 is a side elevation of a modified form of the invention.

Figure 5 is a partial plan of the modification of Figure 4.

Figure 6 is an enlarged sectional view on the line VI—VI of Figure 4.

Referring more particularly to the drawings, the numeral 2 designates a stand upon which there is rotatably supported a shaft 3 which, in turn, carries a coil 4 of extremely long continuous strip material. A stand 5 is disposed adjacent the stand 2 and in alignment therewith, and supports a pair of power driven rolls 6 which may be those of the well known "pinch" type or may, if desired, be the last stand or feed-out device of a continuously operating metal processing machine.

An elevated arcuate-shaped table 7 is disposed adjacent the stand 5, and defines an incline 8 and a decline 9, and is suitably supported by legs 10. It is to be noted that the length of the incline 8, as defined by the line X, is substantially shorter than the length of the decline 9 as defined by the line Y.

The continuous surface of the elevated arcuate-shaped table 7 is provided with a covering of friction-resistant material 12, such as felt or the like, in order that material to be fed thereover will not be subject to scratching, etc.

A flying shear 14 or other intermittently operating metal processing machine is disposed at the bottom of the decline 9 of the elevated arcuate-shaped table 7 to receive the strip material S being fed thereover.

A hatchway limit switch 15 is disposed intermediate the flying shear 14 and the foot of the decline 9 and carries an arm 16 which is adapted to engage a catenary loop S' formed by the strip material S if it is fed too rapidly. The lowering of the arm 16 on the hatchway limit switch 15 effectively retards the rate of feed of the rolls 6 or other equivalent devices at the foot of the incline 8 of the elevated arcuate-shaped table 7 through any suitable and conventional means. As an example, a motor 19 may be provided for driving a speed reducer 18 through a coupling 19a, and this speed reducer connected to the lower 45 of the rolls 6 by a chain 20 and interconnecting companion sprockets 21. This motor 19 is connected to the contacts 15a of the limit switch 15 by a suitable operating circuit, one form of which is illustrated in Figure 1. According to the arrangement of this circuit, when the arm 16 of the limit switch 15 is moved downwardly by the catenary loop S' of the strip S, the contacts 15a of the limit switch 15 are broken, thus deenergizing a relay coil 125 which opens contacts 126. 55

The opening of the contacts 126 necessitates the passage of current from power lines 127 and 128 to the motor 19 by way of a resistance 129, which slows down the motor 19 and thus retards the 5 peripheral speed of the rolls 6 and the strip S therebetween. When the size of the catenary loop S' is decreased by the retardation of the speed of the rolls 6, to such an extent as to be out of contact with the arms 16 on the limit switch 10 15, the contacts 15^a are closed, which results in the energization of the relay 125 and the closing of the contacts 126. In this manner the resistance 129 is "cut out" of circuit from the power lines 127 and 128 to the motor 19, and this causes 15 the latter to resume its previous speed.

It is to be noted from Figure 1 of the drawings that the elevated arcuate-shaped table 7 effectively spans suitable mill equipment which it is desired the strip S should by-pass (in the present 20 instance a dryer and scrubber).

In operation, the strip material S on the coil 4 is fed from the rolls 6 over the incline 8 of the elevated arcuate-shaped table 7. As the strip S moves over the point of emergence of the incline 25 8 and down the decline 9 the latter, being of greater length and weight, exerts a substantial pulling effect. This enables the strip material S to "flow" steadily down the decline 9 and toward and into the flying shear 14. If the intermediate 30 operation of the flying shear 14 causes an excess of the strip S to momentarily form a catenary loop S' at the foot of the decline 9, the arm 16 of the hatchway limit switch 15 will be depressed and effect the retardation of the rolls 6 or other 35 feeding device.

Referring to Figure 4 of the drawings, a modified form of the invention contemplates the provision of a plurality of friction-resistant idle rollers 17 on the surface of the elevated arcuate-shaped table 7 in lieu of the felt 12. 5

While I have shown and described several specific embodiments of my invention, it is to be understood that I do not wish to be limited exactly thereto, since various modifications may be made without departing from the scope of my 10 invention, as defined in the following claims.

I claim:

1. Conveying apparatus for continuous strip material comprising a table having an inclined portion and a declined portion, and means solely at 15 the foot of the inclined portion of said table for moving said material over said inclined portion, the declined portion of said table being of sufficiently greater length than the inclined portion thereof to permit the material thereon to act 20 by its own weight to pull itself forwardly with respect to said table.

2. Conveying apparatus for continuous strip material comprising a table having an inclined portion and a declined portion, means solely at 25 the foot of the inclined portion of said table for moving said material over said inclined portion, the declined portion of said table being of sufficiently greater length than the inclined portion thereof to permit the material thereon to act 30 by its own weight to pull itself forwardly with respect to said table, and means in contact with said material for controlling the operation of said first named means.

CARL E. MOORE. 35
